UNITED STATES PATENT OFFICE.

CHARLES H. DIXON, OF NEWARK, NEW JERSEY.

CONVERTIBLE CHAIR AND TABLE.

No. 884,136.

Specification of Letters Patent.

Patented April 7, 1908.

Application filed June 26, 1907. Serial No. 380,916.

To all whom it may concern:

Be it known that I, CHARLES H. DIXON, a citizen of the United States, residing at Newark, in the county of Essex, State of New Jersey, have invented certain new and useful Improvements in Convertible Chairs and Tables; and I do hereby declare the following to be a full, clear, and exact description of the invention, such as will enable others skilled in the art to which it appertains to make and use the same.

The present invention has reference to convertible chairs and tables, and it aims to provide an exceedingly simple and durable piece of furniture which can be effectively converted from a chair into a table by causing the back to assume a horizontal position.

To this end the invention consists in certain details of construction, and in the combination and arrangement of parts herein-after fully described, specifically claimed, and illustrated in the accompanying drawings, in which like parts are designated by corresponding reference numerals in the several views.

Of the said drawings, Figure 1 is a side elevation of the improved piece of furniture, showing the same converted into a chair, Fig. 2 is a front elevation thereof, Fig. 3 is a side elevation of the piece of furniture converted into a table, Fig. 4 is a vertical section taken on the line 4—4 of Fig. 2, Fig. 5 is a vertical section taken on the line 5—5 of Fig. 1.

In its practical embodiment, the chair comprises front and rear legs 7, 7, and 8, 8, a seat 9 carried by said legs, and a back 10 which is hinged to the rear end of the fixed arms 11 and forms the top of the table, when the piece of furniture is to be used for that purpose. The seat above-referred to is located between the upper and lower ends of the several legs and is secured thereto in any desired manner. The seat, moreover, is of the "box" type, thus providing a receptacle in which various articles may be placed. The cover 12 of the box, which forms the upper wall of the seat, is hinged at its rear edges to the rear wall 13 of the seat and rests, when closed, upon horizontal flanges or shoulders 14 and upon the front wall 15 of the seat.

Each of the arms 11 which are mounted upon upper ends of the legs has secured to its upper face, at the rear end thereof, one member of a hinge 16, the opposite member of

which is fastened to a beam 17 which is fastened to the under face of the table top or chair back 10. The position of these beams is such that they rest directly upon the upper faces of the arms 11, when the piece of furniture is converted into a table while they aline directly with and may be regarded as extensions of the rear legs 8, when the piece of furniture is to be used as a chair. Between the beams and in spaced relation thereto and to each other is disposed a series of ribs 18 which are likewise secured to the under face of the table top and are further connected at their opposite ends by beams 19 and 20, the former of which fits exactly between the beams 17 and is connected to the adjacent end thereof, while the latter fits between the rear legs 8, the length of the ribs being such that the last-mentioned beam rests upon the upper edge of the rear wall of the box seat, when the table top is in its vertical position. Each rear leg is further provided with a hook 21 pivoted thereto and adapted for engagement with an eye-bolt 22 which is secured to the table top adjacent the lower end thereof thus retaining the top in its vertical position. The arms may, if desired, be supported by a series of ribs 24 which fit at opposite ends in sockets formed in the under face of said arms and in the upper face of the adjacent side walls of the seat.

It will be apparent, therefore, that the piece of furniture may be readily converted from a table to a chair and vice versa by merely changing the position of the swinging member 10, and that the latter will be retained in its vertical position even in the event of injury to the hinges, by means of the engagement of the hooks and eye-bolts, and by the disposition of the beam 20 between the rear legs 8.

The piece of furniture may be constructed in various sizes, and its lines may obviously vary somewhat from those shown in the present instance.

What is claimed, is,

A chair of the class described comprising in combination front and rear legs; a seat carried by said legs and disposed intermediate the ends thereof; arms mounted upon the upper ends of the said legs; a back adapted to be swung into vertical or horizontal position, and having a pair of beams secured to its under face in direct alinement with the rear legs of the chair, each beam being hinged at its lower end to the rear end of the adja-

cent arm; a series of ribs secured to the under face of said back in spaced relation to and parallel with each other and with themselves; beams connecting the opposite ends of said 5 ribs, the upper beam fitting between said first-mentioned beams, and the lower beam fitting between the rear legs of the chair and resting upon the upper edge of the rear wall of the chair seat, when the back is in its vertical 10 position; hooks secured to the said rear legs; and eyes secured to the under face of said back and adapted for engagement with

said hooks, to retain the back in vertical position, said first-mentioned beams being adapted to contact directly with the upper face of 15 said arms, when the back is in its horizontal position.

In testimony whereof, I affix my signature, in presence of two witnesses.

CHARLES H. DIXON.
